US00D936702S

(12) **United States Design Patent** (10) Patent No.: **US D936,702 S**
(45) Date of Patent: **** Nov. 23, 2021**

(54) **ELECTRONIC DEVICE WITH ANIMATED GRAPHICAL USER INTERFACE**

(71) Applicant: **Apple Inc.**, Cupertino, CA (US)

(72) Inventors: **Kevin Will Chen**, Cupertino, CA (US); **Teofila Connor**, San Francisco, CA (US); **Alan C. Dye**, San Francisco, CA (US); **Thalia Jimena Echevarria Fiol**, Cupertino, CA (US); **Aurelio Guzmán**, San Jose, CA (US); **Jonathan P. Ive**, San Francisco, CA (US); **Vincenzo Vuono**, Palermo (IT); **Wan Si Wan**, Sunnyvale, CA (US); **Christopher I. Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/767,520**

(22) Filed: **Jan. 22, 2021**

Related U.S. Application Data

(63) Continuation of application No. 29/693,253, filed on May 31, 2019, now Pat. No. Des. 914,056.

CLAIM

The ornamental design for an electronic device with animated graphical user interface, as shown and described.

DESCRIPTION

FIG. 1 is a front view of a display screen or portion thereof with animated graphical user interface showing a first image of the claimed design;
FIG. 2 is a second image thereof;
FIG. 3 is a third image thereof;
FIG. 4 is a fourth image thereof;
FIG. 5 is a fifth image thereof;

FIG. 6 is a sixth image thereof;
FIG. 7 is a seventh image thereof;
FIG. 8 is an eighth image thereof;
FIG. 9 is a ninth image thereof;
FIG. 10 is a tenth image thereof;
FIG. 11 is an eleventh image thereof;
FIG. 12 is a twelfth image thereof; and,
FIG. 13 is a front view of an electronic device having a display screen with the animated graphical user interface of FIG. 1 applied to the display screen. The animated graphical user interface design of FIGS. 2-12 may be similarly applied thereto.

The outer broken lines in the figures show a display screen or portion thereof, or an electronic device having a display screen, and form no part of the claimed design. The other broken lines in the figures show portions of the animated graphical user interface that form no part of the claimed design.

The appearance of the animated image sequentially transitions between the images shown in FIGS. 1-12. The process or period in which one image transitions to another forms no part of the claimed design.
